CLAIM

The ornamental design for an electric motorcycle as shown and described.

DESCRIPTION

FIG. 1 is a top perspective view showing the top, front, and left sides of an electric motorcycle;

FIG. 2 is a top perspective view showing the top, rear, and right sides of the electric motorcycle;

FIG. 3 is a bottom perspective view showing the bottom, rear, and left sides of the electric motorcycle;

FIG. 4 is a left side elevation view of the electric motorcycle;

FIG. 5 is a right side elevation view of the electric motorcycle;

FIG. 6 is a front elevation view of the electric motorcycle;

FIG. 7 is a rear elevation view of the electric motorcycle;

FIG. 8 is a top plan view of the electric motorcycle; and,

FIG. 9 is a bottom plan view of the electric motorcycle.

The portions shown in broken lines show environment and form no part of the claimed design.

1 Claim, 8 Drawing Sheets
